No. 685,120.

Patented Oct. 22, 1901.

J. B. ERWIN & J. N. MOEHN.
CAR STARTER AND MOVER.

(Application filed Dec. 3, 1900.)

(No Model.)

UNITED STATES PATENT OFFICE.

JAMES B. ERWIN AND JOHN N. MOEHN, OF MILWAUKEE, WISCONSIN.

CAR STARTER AND MOVER.

SPECIFICATION forming part of Letters Patent No. 685,120, dated October 22, 1901.

Application filed December 3, 1900. Serial No. 38,392. (No model.)

To all whom it may concern:

Be it known that we, JAMES B. ERWIN and JOHN N. MOEHN, citizens of the United States, residing at Milwaukee, county of Milwaukee, 5 and State of Wisconsin, have invented new and useful Improvements in Car Starters and Movers, of which the following is a specification.

Our invention relates to improvements in 10 that class of car starters and movers by which the necessary power for moving the car is applied through a compound lever to the periphery of the car-wheel.

Our improvement pertains more especially, 15 first, to the construction of the fulcrum or pivotal support of the so-called "primary lever," which rests upon one of the rails of the car-track; second, to the device for retaining such lever in place upon the rail as it is being shoved forward behind the moving car, and, third, to the device for retaining the two parts of which the compound lever is formed in their proper relative positions to each other. 20

The construction of our invention is explained by reference to the accompanying drawings, in which—

Figure 1 represents a top view, and Fig. 2 is a longitudinal section drawn on line $x-x$ of Fig. 1.

30 Like parts are identified by the same reference-letters in both views.

A is the primary lever, which is pivotally supported upon the track B by the revoluble fulcrum C. The fulcrum C is supported between the vertical walls D D of the recess E upon the bolt or pin F.

G is the short arm of the primary lever A, which is adapted to engage beneath the periphery of the car-wheel.

40 H H are downwardly-projecting lugs, which are formed integral with the walls D D of the lever and extend downward a short distance below the fulcrum C, so as to engage upon the respective sides of the railway-rail B, 45 whereby said lever is retained upon the track as it is being pushed forward upon the same behind the moving car.

The side walls D D form the long arm of the primary lever, which lever is pivotally connected with the secondary lever J by the bolt K.

L is the short arm of the secondary lever,

which is also adapted to engage against the periphery of the car-wheel as said levers are forced forward between the convex surface 55 of the wheel and the track. While the lever J may, if desired, be formed of metal entire, it is preferably provided with a socket N, in which is inserted a wooden handle M, of any desired length. The front end of the arm L 60 is provided with an extension-piece O, which is secured in place between the walls P P of said arm by the pivotal bolt Q. The primary lever A is limited in its upward movement between said side walls D D by the cross-piece R, which is cast integral with said side walls, and is also limited in its downward movement by the bolt or pin S, which is supported at its respective ends in said side walls D and extends across from one wall to 70 the other beneath said primary lever. The cross-piece R and pin S not only serve as stops to the upward-and-downward movement of the primary lever, but they perform an additional function by connecting together 75 and strengthening the walls P of said arms and prevent the liability of such arms being sprung apart and broken by excessive pressure to which they are subjected. The fulcrum C is preferably formed of hardened steel 80 or other hard metal and is hexagonal in cross-section, the surfaces T between the angles of the hexagon being slightly concave, so as to form sharp points at such angles, which points are adapted to engage in the surface 85 of the railway-rail and prevent the lever from slipping rearward as the same is applied to the periphery of the car-wheel. By thus making the surfaces T of the fulcrum slightly concave between the contact-points two separate contact-points or bearings U are brought into contact with the rail at the same time, whereby two important objects are attained—i. e., first, the pressure brought to bear upon the fulcrum is subdivided between such 95 points, whereby they are less liable to become dull or broken by contact with the rail, and, second, by thus providing the fulcrum with two contact-points at equal distances from the vertical center of said fulcrum the 100 base of the fulcrum is broadened, and the fulcrum is thereby prevented from rotating backwardly upon the rail as pressure is applied to the wheel. As the points U upon

the rail are liable to become dull or blunt, the fulcrum may be turned on its supporting-bolt F, so as to bring the other points U in contact with the rail, whereby the life of 5 said fulcrum is prolonged.

While we have shown the short arm of the lever in two parts, so that the same may be extended by turning the extension-piece O forward upon its supporting-pivot Q, said 10 parts O and L may, if desired, be formed integral.

We are aware that a cylindrical roller having a serrated surface has previously been used as a fulcrum to a one-armed lever, as shown in 15 United States Patent No. 504,535; but owing to the cylindrical shape of such fulcrum a pawl and ratchet are used, and necessarily used, to prevent said roller from turning backwardly as the lever is applied to a car- 20 wheel, while by our improvement the fulcrum is given a broad base, which is practically the same as if it were rectangular in shape, and it has no more tendency to rotate backward than a rectangular block would 25 have, whereby the necessity of employing a pawl and ratchet to prevent rearward rotation of the pawl is avoided, while by making the surface between the angles of the fulcrum concave such angles are more acute and

are thereby caused to engage in the surface 30 of the rail.

Having thus described our invention, what we claim as new, and desire to secure by Letters Patent, is—

1. In a car starter and mover, a primary lever, comprising a short arm G; two vertical walls D, D forming the long arm thereof; cross-piece and a cross-pin S, in combination with a revoluble fulcrum C; secondary lever J; and pivotal bolt or fulcrum K, substantially as set forth. 35

2. In a car starter and mover, a primary lever, comprising a short arm G; two vertical walls D, D, forming the long arm thereof; cross-piece R; and cross-pin or stop S, in combination with the secondary lever J; pivotal bolt K; and a revoluble hexagonal fulcrum C, said fulcrum C being prevented, by its breadth of base, from rolling rearwardly when under pressure, as set forth. 45

50 In testimony whereof we affix our signatures in the presence of two witnesses.

JAMES B. ERWIN.
JOHN N. MOEHN.
